[57] CLAIM

The ornamental design for a retainer for eyeglasses, as shown and described.

DESCRIPTION

FIG. 1 is a perspective view of a retainer for eyeglasses showing my design;

FIG. 2 is a top plan view thereof, the bottom view being identical;

FIG. 3 is a left side elevational view thereof, the right side being identical;

FIG. 4 is a rear elevational view thereof; and,

FIG. 5 is a front elevational view thereof.

The temples in FIG. 1 are shown in broken lines for illustrative purposes and form no part of the claimed design.
